of Delaware

Application August 19, 1930. Serial No. 476,392

7 Claims. (Cl. 250—27)

This invention is a method for controlling the activation and heating of the filament of the usual vacuum tube.

The filament of the ordinary vacuum tube is heated by the A battery which has to be switched on manually when the device is to be used, and which should be switched off when the tube is no longer in use. In contradistinction to this, and according to this invention, a circuit arrangement is provided whereby voice or other modulations impressed on the microphone transformer circuit automatically cause the heating of the filament, and when the modulations cease, the heating of the filament ceases.

15. This is effected by an arrangement of the circuit in such manner that impressions of the voice or other characteristic on the microphone cause the circuit to function as a switch and permits the completion of the filament circuit during the period of the impression of the modulations on the microphone.

More specifically, in one embodiment of the invention, there is provided across the filament circuit a gas filled discharge tube of the Geissler type, which may be filled with some gas as argon, krypton, helium or the like.

This gas filled tube when subjected to alternating current, will permit the passage through it of the current from the A battery and through the filament. When subjected to high or low frequency oscillations which are present in the microphone transformer circuit, it becomes conductive and permits the flow of current from the A battery through the filament. As soon as these oscillations cease, the gas in the tube becomes non-conductive again.

The gas filled tube shunts the filament circuit, and is preferably connected across the primary of the microphone transformer.

40. Another embodiment of the invention eliminates the use of a gas filled tube by introducing the filament current directly into the microphone transformer with the filament and filament power source in series with one input terminal thereof. In this way the diaphragm of the microphone, by the impression of characteristics on it, completes the filament circuit, thereby activating the filament and permitting activation of the tube.

50. I have found that a source voltage considerably greater than the rated filament capacity of the tube is required for proper filament activation because of the short duration of the closed circuit, activated directly by the impression of 55. voice characteristics upon the microphone di-

aphragm. Under test conditions where the rated filament voltage of the tube was two volts, six volts were necessary to produce proper activation. However, this ratio would differ with the type of microphone used and could more properly be computed by comparison of the amperage draw of the microphone, the primary of the microphone transformer and the filament of the tube used.

This invention is not limited to use with one tube, but may be used with a plurality of tubes.

In the drawing illustrating possible embodiments of the invention,

Fig. 1 shows the preferred way of carrying out the invention,

Fig. 2 shows another way of carrying out the invention with a three element tube.

Fig. 3 shows another way of carrying out the invention.

Referring now to the drawing, showing a 75 simple circuit in which the control element and plate of a thermionic discharge device T are associated with both means for impressing modulations on the control device and means for translating said characteristics, a microphone 80 1 having usual primary transformer 2 and secondary 5 has one terminal of the input connected to the terminal of the filament 3 of the thermionic discharge device T, the other terminal of which is connected through source of 85 current 4 to one terminal of the microphone. Shunted across the two transformer input terminals with which the filament terminals are in circuit is a gas filled discharge tube 7, preferably of the Geissler type. A condenser 6 may be 90 bridged across the microphone, for preventing arcing during switching. Oscillations in the secondary 5 of the transformer are impressed on the grid through conductors 5a and 5b, a variable condenser 5c being inserted in this circuit 95 for obtaining clarity of tone, condenser 5c acting to filter out undesirable oscillations, outside of the normal band of the microphone secondary.

Conductor 13 and battery B complete the plate circuit.

In operation, voice or other modulations impressed on the microphone 1 set up oscillations in tube 7 which make it conductive, thereby completing a circuit from power source 4, through conductors 10 and 11, tube 7, conductor 12 and filament 3. However, while most of the current apparently passes through tube 7, some of it is shunted through the primary 2 of the microphone transformer, through the microphone 1 and conductor 12 to filament 3. 110

When the voice modulations cease, substantially no current passes through the filament 3.

Figure 2 shows a three element tube 15, the filament of which is in circuit through conductors 16 and 17 with battery 18 and the primary 19 of microphone 20. Conductor 14 and battery B complete the plate circuit. In this arrangement, the activation of the filament is directly effected by voice modulations impressed on the microphone. The microphone diaphragm acts as a switch and carries the full current during activation. A small condenser 6' across the microphone prevents arcing during switching.

Figure 3 illustrates the connection of a relay 22 across the output circuit of the microphone transformer 23. The passage of alternating current into the output 24 of the transformer as a result of the impression of signal characteristics on the input of the transformer, effects the closing of the relay which has an independent power source 25 and an armature 26 which completes the filament circuit for such period as alternating current is present in the secondary, that is, when voice or other modulations are present in the primary circuit of the transformer.

I claim as my invention:

1. Filament activating means for a thermionic discharge device comprising in combination with the usual filament and current source therefor, a transformer, the primary of which is in series with the filament, means for impressing modulations on the input circuit of the transformer, and means associated with the transformer and with the filament circuit, for passing current through the filament from its current source only when modulations are impressed on the input of the transformer.

2. Filament activating means for a thermionic discharge device comprising in combination with the usual filament and current source therefor, a transformer, the primary of which is in series with the filament, means for impressing modulations on the input circuit of the transformer, and means associated with the input and output of the transformer, and with the filament circuit, for passing current through the filament from its current source only when modulations are impressed on the input of the transformer.

3. Filament activating means for a thermionic discharge device comprising in combination with the usual filament and current source therefor, of a microphone, a microphone transformer, the

55

80

primary of which is in series with the filament, and means associated with the filament current and with the microphone transformer circuit for passing current through the filament from its current source only when modulations are impressed on the microphone transformer.

4. Filament activating means for a thermionic discharge device comprising in combination with the usual filament and current source therefor, of a microphone, a microphone transformer, the primary of which is in series with the filament, and means associated with the input and the output of the microphone transformer, and with the filament circuit, for passing current through the filament from its current source only when modulations are impressed on the microphone transformer circuit.

5. Automatic means for the activation of the filament in a thermionic discharge device, having the usual power source in circuit with the filament, the combination of a microphone, and a microphone transformer, the primary of the transformer being in series with the filament and its power source, whereby currents set up in the primary of the transformer pass through the 100 filament and heat it.

6. In combination with a thermionic discharge device having the usual filament and power source therefor, a microphone, a microphone transformer, the primary of the transformer being in circuit with the filament and its power source, and an element in shunt across the aforementioned circuit which is normally non-conductive, but which becomes conductive when voice or other modulations are impressed on the 110 primary of the transformer, and transmits current from the filament power source for heating the filament.

7. In combination with a thermionic discharge device having the usual filament and power source therefor, a microphone, a microphone transformer, the primary of the transformer being in circuit with the filament and its power source, and an element having the characteristics of a Geissler tube, in shunt across the aforementioned circuit which is normally non-conductive, but which becomes conductive when voice or other modulations are impressed on the primary of the transformer, and transmits current from the filament power source for heating 125 the filament.
